UNITED STATES PATENT OFFICE.

HARRY BATES, OF NEW YORK, N. Y., ASSIGNOR TO UNDERWOOD TYPEWRITER COMPANY, OF NEW YORK, N. Y., A CORPORATION OF DELAWARE.

TYPEWRITING-MACHINE.

1,350,000.

Specification of Letters Patent. Patented Aug. 17, 1920.

Application filed March 15, 1919. Serial No. 282,891.

To all whom it may concern:

Be it known that I, HARRY BATES, a citizen of the United States, residing in New York city, in the county of New York and State of New York, have invented certain new and useful Improvements in Typewriting-Machines, of which the following is a specification.

This invention relates to typewriting machines, and more especially to what are sometimes known as word-centering devices. The invention is herein described as applied to an Underwood typewriting machine, in which the revoluble platen is journaled in a traveling carriage.

One primary utility of such devices is to enable words, such as headings, to be rapidly and accurately centered upon a work-sheet in the machine. In the structure illustrated herein, the typewriter carriage may be provided both with the usual pointer, which serves to indicate the position of the carriage, and with an extra centering pointer. The latter may be adapted to be shifted by manipulating a lever or coupling mechanism, so that by a series of manipulations or operations thereof, the centering pointer may be shifted along the carriage. This will enable it to indicate upon the usual scale-plate the point at which the writing is to be begun if the center of the writing is to come at the point indicated by the usual scale-pointer.

Other features and advantages will hereinafter appear.

35 In the accompanying drawings,

Figure 1 is a fragmentary perspective, showing the device applied to an Underwood typewriting machine.

Fig. 2 is a front view, largely sectional, 40 showing the mounting of the centering pointer as it normally rests.

Fig. 3 is a similar view, showing the operating handle depressed.

Fig. 4 is a dissected perspective view, 45 showing the structure on which the centering pointer slides.

Fig. 5 is a diagrammatic plan view, showing the pointers set before beginning to count.

50 Fig. 6 is a similar view, showing the centering pointer having counted off a word or title of twenty letter-spaces.

Fig. 7 shows the carriage set to write the title.

Fig. 8 shows the position of the carriage 55 at the end of writing the title.

In the usual Underwood typewriting machine, the revoluble platen 10 is journaled in a frame 11 in the carriage 12, which travels from right to left. Whenever a 60 character-key 13 is depressed it carries down its key-lever 14 to swing its type-bar 15 upwardly and rearwardly, so that the type 16 thereon will print upon a work-sheet 17, passed around the platen. The type prints 65 upon the inserted work-sheet at a point in the travel of the carriage, indicated by the usual carriage-pointer 18 upon the usual scale-plate 19 at the front of the machine 70 frame, and in printing feeds along the carriage by the usual escapement wheel 20, which the actuated type controls by the usual dogs 21, said dogs, in turn, being operated by the universal bar 22, which the usual heel 23 upon the type-bar 15 strikes 75 as it approaches the platen 10.

The machine is also provided with the usual right and left-hand margin-stops, which serve to limit the travel of the carriage in either direction and have attached 80 to them pointers 24 and 25, overlying the scale-plate 19.

To center any line of writing upon the work-sheet 17, a centering pointer 26 may be positioned by a character-counter 27. The 85 character-counter comprises the lever 28, pivoted within the casing 29 of the counter, and which, when depressed, is adapted to advance the casing along the rack 30 fast to the front bar 31 of the typewriter carriage. 90 The teeth of the rack are spaced on centers at half the spacing of the divisions on the scale 19, with the result that each depression of the lever 28 advances the casing half a letter-space. When, therefore, the total 95 number of letters and spaces in the desired line are counted off on the lever, the casing 29 will have advanced both itself and the centering pointer 26, fast to it, half the letter-space travel of the typewriter carriage needed for writing the desired line.

The easiest way to center the desired line is to start the aforesaid counting with the pointer 26 at the desired central letter-space

of the line (illustrated as letter-space 40 in Fig. 5), and when the counting is finished, note the position of the character-counter 27 on the scale 19 by it (*i. e.*, letter-space 5 30 in Fig. 6), then move the carriage to the right to bring the pointer 18 to that position (Fig. 7), and begin writing the line from that position. Since this position is half the letter-spaces in the line, to one side of 10 the first position of the carriage, the center of the written line will fall at the first position of the carriage, and the writing will end at the Fig. 8 position.

The connections, whereby the lever moves 15 the casing along the rack, include a pawl 32, pivoted on an extension 33 of the lever 28 and a ratchet-wheel 34, journaled on a transverse shaft 35, which also forms the pivot of the lever 28. The ratchet-wheel constitutes 20 a pinion constantly in mesh with the rack 30. The pawl 32 is normally pressed by a spring 35^a, so that when actuated it goes into the teeth of the ratchet, and to enable 25 the casing to be drawn to its left-hand position, the pawl 32 may be cammed clear of the ratchet by a spring 36^a, which swings the lever 28 upward, so that an extension 36 of the pawl 32 rests on a cam lug 37 and the pawl is then clear of the ratchet-wheel. The 30 lever may terminate in a thumb-piece 38, which is easily grasped, and be provided with a lug 39, which arrests it at the bottom of its throw by striking the top of the casing 29. The casing, surrounding the rack 30, may 35 comprise a rear bar 42, having an L-bottom 43 adapted to rest on the top of the front bar 31, and a front bar 44 adapted to be held to the bottom 43 by screws 45 entering lugs 46. The front plate or bar 44 has a lug 47 at 40 each end, which extends downwardly and then in under the front bar 31, so that a set-screw 48 threaded through each lug may be set up against the bottom of the front bar 31, thus holding the rack 30 in place. The rack 45 may be fastened in the casing by screws 49 passing through it and threaded into lugs 50 projecting inwardly at the ends of the casing; and the casing may include a slot at the front, just above the bottom 43 cut at 50 51 from the bottom of the front plate 44, thus permitting the centering pointer 26 to be formed as an extension 52, held by screws to one side of the U-frame 53 within the counter-casing. The extension 52 projects 55 outwardly through the cut 51 and slightly upwardly. A further extension 54 of the extension 52 lies parallel to the front bar 31, thus permitting the centering pointer, when farthest to the left, to overlie and point to 60 the same scale division as the pointer 18.

For convenience in assembling, the front 55 of the casing 29 may be attached to the main body by screws 56 threaded into lugs 57 on the body. A stiff flat spring 58 fast to the 65 bottom of the U-frame 53 holds the pointer

26 and its casing 29 upright. The U-frame may be held to the casing 29 by screws threaded into the U-frame and passing through holes 59 in an apron 60, depending from the casing 29 and connected thereto 70 by a shelf 61, comprising an opening 62 to clear the head of the shaft 35. To center the teeth 30 accurately with reference to the scale 19, one of the set-screws 48 enters a depression 63, Fig. 2, in the under side of the 75 bar 31.

Variations may be resorted to within the scope of the invention, and portions of the improvements may be used without others.

Having thus described my invention, I 80 claim:

1. In a typewriting machine, the combination with a typewriter frame and a traveling carriage, of a revoluble platen, a scale on the frame, a pointer upon the carriage 85 adapted to normally occupy one position upon the carriage, and a counting device for moving said pointer step by step to another point on the carriage.

2. In a typewriting machine, the combination with a typewriter frame and a traveling carriage, of a revoluble platen, a scale on the frame adapted to indicate letter-space positions of the carriage, a pointer on the carriage adapted to normally occupy one 95 position, and a counting device for moving said pointer by half letter-space steps to another position upon the carriage.

3. In a typewriting machine, the combination with a typewriter frame and a traveling carriage, of a revoluble platen, a scale on the frame adapted to indicate letter-space positions of the carriage, a pointer on the carriage adapted to normally occupy one position, a counting device for moving said 100 pointer by half letter-space steps to another position upon the carriage, and a fixed pointer fast to the carriage, so that when the first pointer occupies one position, and then the carriage is shifted to bring the fixed 105 pointer to that position, typewritten matter counted by the counting device will be centered at the point first occupied by the fixed pointer.

4. In a typewriting machine, the combination with a typewriter frame and a traveling carriage, of a revoluble platen, a scale on the frame, a rack upon the carriage, a pointer adapted to travel upon said rack, and a lever for causing the travel of the 110 pointer and adapted to move the pointer one-half scale division at each operation of the lever.

5. In a typewriting machine, the combination with a typewriter frame and a traveling carriage, of a revoluble platen, a scale on the frame, a rack upon the carriage, a pointer adapted to travel upon said rack, a lever for causing the travel of the pointer 115 and adapted to move the pointer one-half 120

125

scale division at each operation of the lever, a pointer fixed upon the carriage, and a stop for the first-named pointer to cause it to be arrested at one limit of its travel in a position identical with the fixed pointer.

5 6. In a typewriting machine, the combination with a traveling carriage, of a rack upon the carriage, a pointer movable along said rack, a housing to which the pointer is fast, a pinion in said housing meshing with the rack, a pawl for turning said pinion, and a lever for driving said pawl.

10 7. In a typewriting machine, the combination with a traveling carriage, of a rack upon the carriage, a pointer movable along said rack, a housing to which the pointer is fast, a pinion in said housing meshing with the rack, a pawl for turning said pinion, a lever for driving said pawl, and a lug at 15 one end of the throw of the pawl to lift it to ineffective position, to permit the housing to be moved along the rack.

15 8. In a typewriting machine, the combination with a typewriter frame and a traveling carriage, of a revolute platen, a scale on the frame, a bar forming part of said carriage, a rack adapted to be detachably mounted upon said bar, a pointer movable along said rack, a lever, and a pinion meshing with the rack and operated by the lever 20 for moving the pointer.

25 9. In a typewriting machine, the combination with a typewriter frame and a traveling carriage, of a revolute platen, a scale on the frame, a bar forming part of the carriage, a housing adapted to be detachably mounted upon said bar, a rack in said housing, and a pointer adapted to be positioned along said rack.

30 10. In a typewriting machine, the combination with a typewriter frame and a traveling carriage, of a revolute platen, a scale on the frame, a bar forming part of the carriage, a housing adapted to be detachably mounted upon said bar, a rack in said housing, a pointer adapted to be positioned along said rack, a second housing fast to 35 said pointer, a pinion in said second housing meshing with the rack, and a lever for rotating said pinion to move the pointer along the rack.

40 11. In a typewriting machine having a frame, the combination with a traveling carriage and a scale upon the frame divided in letter-space divisions, of a pointer fast to 45 said carriage for pointing-off letter-space divisions upon said scale, and a second pointer movably mounted upon said carriage to coöperate with the first pointer in centering written work upon a work-sheet.

45 12. In a typewriting machine having a frame, the combination with a traveling carriage and a scale upon the frame divided in letter-space divisions, of a pointer fast to 50 said carriage for pointing-off letter-space

divisions upon said scale, a second pointer movably mounted upon said carriage to coöperate with the first pointer in centering written work upon a work-sheet, and a device for setting said second pointer at half-letter-spaces away from the first pointer.

55 13. The combination with a housing adapted to be attached to a typewriting machine, of lugs for attaching it, set screws in said lugs adapted to engage the typewriting machine, a rack in the housing, and a pointer adapted to be set by said rack upon the typewriting machine.

60 14. The combination with a housing adapted to be attached to a typewriting machine, of lugs for attaching it, set screws in said lugs adapted to engage the typewriting machine, a rack in the housing, a pointer adapted to be set by said rack upon the typewriting machine, a secondary housing 65 fast to said pointer, and a finger-piece for positioning said secondary housing upon said rack.

70 15. The combination with a housing adapted to be attached to a typewriting machine, of lugs for attaching it, set screws in said lugs adapted to engage the typewriting machine, a rack in the housing, a pointer adapted to be set by said rack upon the typewriting machine, a secondary housing 75 fast to said pointer, a finger-piece for positioning said secondary housing upon said rack, a pinion on which said finger-piece is effective, said pinion meshing with said rack, and means for slidably holding the secondary 80 housing upon the first housing.

85 16. In a typewriting machine, the combination with a traveling carriage, of a pointer therefor, a secondary pointer, carried on the carriage but shiftable thereon, a scale, divided in letter-space intervals, with which the first pointer coöperates, and means for variably positioning the secondary pointer at half letter-spaces away from the first pointer.

90 17. In a typewriting machine, the combination with a typewriter frame and a letter-feeding carriage, of a scale on the frame, a pointer upon the carriage adapted to normally occupy one position upon the carriage, and a counting device for moving said pointer step by step to another point on the carriage.

95 18. In a typewriting machine, the combination with a typewriter frame and a letter-feeding carriage, of a scale on the frame adapted to indicate letter-space positions of the carriage, a pointer on the carriage adapted to normally occupy one position, and a counting device for moving said 100 pointer by half letter-space steps to another position upon the carriage.

105 19. In a typewriting machine, the combination with a typewriter frame and a letter-feeding carriage, of a scale on the frame 110

4
adapted to indicate letter-space positions of the carriage, a pointer on the carriage adapted to normally occupy one position, a counting device for moving said pointer by half letter-space steps to another position upon the carriage, and a fixed pointer fast to the carriage, so that when the first pointer occupies one position, and then the carriage is shifted to bring the fixed pointer to that position, typewritten matter counted by the counting device will be centered at the point first occupied by the fixed pointer.

10 20. In a typewriting machine, the combination with a typewriter frame and a letter-feeding carriage, of a scale on the frame, a rack upon the carriage, a pointer adapted to travel upon said rack, and a lever for causing the travel of the pointer and adapted to move the pointer one-half scale 15 division at each operation of the lever.

15 25. In a typewriting machine, the combination with a typewriter frame and a letter-feeding carriage, of a scale on the frame, a rack upon the carriage, a pointer adapted to travel upon said rack, a lever for causing the travel of the pointer and adapted to move the pointer one-half scale division at each operation of the lever, a pointer fixed 20 upon the carriage, and a stop for the first- 30 named pointer to cause it to be arrested at one limit of its travel in a position identical with the fixed pointer.

22. In a typewriting machine, the combination with a typewriter frame and a letter-feeding carriage, of a scale on the frame, a bar forming part of said carriage, a rack adapted to be detachably mounted upon said bar, a pointer movable along said rack, a lever, and a pinion meshing with the rack and operated by the lever for moving the 35 pointer.

40 23. In a typewriting machine, the combination with a typewriter frame and a letter-feeding carriage, of a scale on the frame, a bar forming part of the carriage, a housing adapted to be detachably mounted upon said 50 bar, a rack in said housing, and a pointer adapted to be positioned along said rack.

24. In a typewriting machine, the combination with a typewriter frame and a letter-feeding carriage, of a scale on the frame, a bar forming part of the carriage, a housing adapted to be detachably mounted upon said bar, a rack in said housing, a pointer adapted to be positioned along said rack, a second housing fast to said pointer, a pinion in said second housing meshing with the rack, and a lever for rotating said pinion to move the pointer along the rack. 45 55
